UNITED STATES PATENT OFFICE.

GEORGE E. WEBB, OF MILWAUKEE, WISCONSIN, ASSIGNOR TO KOEHRING COMPANY, OF MILWAUKEE, WISCONSIN, A CORPORATION.

PAVEMENT-FINISHING MACHINE.

Application filed April 17, 1922. Serial No. 553,990.

The present invention relates to a road finishing machine which is of that general type in which a roller is utilized for acting upon the freshly deposited aggregate while it is still plastic, to shape and compact the same in the desired manner.

The finishing machine is well adapted for use in the construction of concrete roads and pavements, and is adapted to travel upon the side forms or rails which are erected upon the subgrade at the sides of the road and serve to confine the freshly deposited concrete within the desired area between the road rails and to shape the sides of the road or pavement being formed, the side forms or road rails being progressively advanced along the subgrade as the road building proceeds.

The freshly mixed and plastic concrete aggregates are deposited progressively upon the subgrade by some conventional form of paver or mixer, and this concrete is acted upon mechanically by the finishing machine to compact and shape the same, with the result that a dense concrete is obtained and the aggregate is so disposed and distributed as to give a superior wearing surface.

The pressure and mechanical action of the device upon the concrete tends to bring to the surface surplus water and grout so that a good finish can be obtained, and the machine can be used to advantage upon dry mixes of concrete. In this connection it may be mentioned that it has been found by experience that the best and most durable roads are produced where the concrete is mixed with a minimum amount of water and what is termed a dry mix is employed. Obviously these so called dry mixes of concrete are stiffer and more difficult to shape than the wet and comparatively plastic concrete mixes, and a more efficient finishing machine is required to act upon the dry mixes and obtain the desired results.

The finishing machine is provided with one or more rollers which extend across the road way, and which are maintained in contact with the concrete or other plastic road forming material by the weight of the machine. The rollers are adjustable and may either be positively driven or permitted to idle along with the work as the machine progresses. Mechanism may also be pro-

vided for reciprocating the rollers longitudinally when such an action is found desirable.

The machine may also be provided with a finishing float which follows the rollers and imparts the final smoothing or finishing action upon the surface of the concrete. The finishing machine is assembled as a unit, and is adapted to be propelled over the subgrade and plastic road forming material while supported upon the side forms or road rails, the necessary mechanism being provided for adjusting the positions of the operating parts, and selectively applying driving power thereto, as may be necessary to obtain the desired results.

For the purpose of explaining the invention one particular embodiment thereof will be illustrated and described in detail, although it will be obvious that many modifications and changes can be made in the details of construction and that the invention is susceptible of other embodiments without departing from the spirit thereof and within the scope of the claims.

In the accompanying drawings:

Figure 1 is a front elevation of one end of the pavement finishing machine, parts being broken away.

Figure 1^A is an elevation of the opposite end of the machine, parts being broken away.

Figure 2 is a top plan view of the end of the machine which is illustrated by Figure 1.

Figure 2^A is a similar view of the end of the machine which is illustrated by Figure 1^A.

Figure 3 is an end view of the pavement finishing machine.

Figure 4 is a transverse sectional view through substantially the middle portion of the machine, showing the mounting of the roller frame and one of the levers for controlling the transmission of power to the propelling wheels.

Figure 5 is a detail view illustrating the mechanism for tilting the lower supporting frame to adjust the height or elevation of the rollers.

Figure 6 is a detail view of the linkage device which controls the longitudinal reciprocation of the rollers.

Figures 7, 8, 9 and 10 are detail views showing the gearing and connections for transmitting power from the variable speed gearing to the shafts upon which the supporting wheels are mounted.

Figures 11, 12, 13 and 14 are detail views, partly in section, of the gearing which is provided for selectively rotating the rollers and reciprocating the rollers longitudinally.

Figures 15, 16, 17 and 18 are detail views showing the driving mechanism for reciprocating the finishing float when the latter is lowered into operative position.

Figure 19 is a detail view of the locking device which is provided for holding the roller supporting frame in any desired angular position.

Figure 20 is a detail view of the gearing for raising and lowering the roller supporting frame.

Figure 21 is a view of the locking device illustrated by Figure 19, looking at the same from the opposite side thereof.

Figure 22 is a detail view of the selectively controlled clutch device whereby either the gearing for elevating the roller supporting frame or the gearing for tilting the roller supporting frame may be operated at will from the same shaft.

Figures 23 and 24 are detail views of the universal joint on the drive shaft which transmits power to the rollers.

The supporting carriage.

The road finishing elements are mounted upon a carriage which extends transversely across the subgrade and which is adapted to travel upon the usual side forms or road rails 1 between which the plastic concrete or other road building material is confined during the distributing, shaping and finishing operations. The carriage may be constructed or fabricated in any suitable manner and from any available material, and the weight of the carriage is sufficient to hold the concrete finishing members to their work. In the present instance the carriage is shown as comprising a series of similar arched cross pieces 2 which are connected by a series of parallel and longitudinally extending tubular rods 3. The carriage has a length which corresponds to the width of the road to be built, and the ends of the carriage are provided with flanged supporting wheels 4, which are adapted to travel upon the road rails 1. Two of these supporting wheels 4 are illustrated as provided at each end of the carriage, and these wheels are applied to shafts or axles 5 which are journaled within suitable bearings 6, and to which power is selectively applied, as will be hereinafter more fully set forth, for driving or propelling the carriage along the road rails for the purpose of causing the finishing members to act in the necessary manner

upon the freshly deposited and still plastic road building material, as well as for progressively advancing the carriage as the road building operation proceeds. The arched formation of the cross pieces 2 provides the necessary clearance space under the middle portion of the carriage for the various adjustments of the rollers 7 and 8.

The power device for operating and propelling the machine.

By reference to Figure 2 of the drawings it will be observed that an internal combustion engine 9 is mounted upon the top of the carriage at a point toward one end thereof. This engine may be of any suitable construction and may be mounted upon the carriage in any convenient manner. In the present instance the engine is shown as supported by brackets 10 which engage the two uppermost tubular rods 3.

On Figure 1 of the drawings the cooling system for the engine is indicated in a diagrammatic manner at 9^a. The gasoline tank is shown at 9^b and a feed pipe 9^c leads from the gasoline tank to the engine. If desired suitable means may be provided for controlling the engine from one end of the carriage.

The engine shaft 11 extends longitudinally of the carriage and parallel to the tubular rods 3, being journaled at convenient points in its length in bearings 12 on cross bars 13, which are secured to the tubular rods 3. The end of the shaft is connected by a special form of universal joint 14, which will be hereinafter described more in detail, to a drive shaft 15 through which power is conveyed to the rollers for operating the same in the desired manner. At a point toward the end thereof the engine shaft 11 is connected by a conventional worm and worm gear to a transversely extending shaft 16. The worm and worm gear are not shown on the drawing, but are of the well known construction and are housed within the casing 17 through which the shaft 16 extends. This worm gearing greatly reduces the speed so that the shaft 16 revolves at a much slower speed than the engine shaft 11. From the shaft 16 power is taken in any suitable manner as by means of the chain and sprocket connection 18 to a conventional variable speed gearing 19 which is illustrated in a diagrammatic manner on the drawing. This variable speed gearing may be of any conventional construction and by properly shifting the gears provides for a plurality of forward speeds and also for a reverse speed. The worm gear casing 17 and the variable speed gear 19 are both mounted upon the uppermost tubular rods 3 at the top of the carriage and, as will be hereinafter set forth, power is transmitted through the variable speed gear 19 to the supporting

wheels 4 for propelling the carriage, while power is taken from the worm gear shaft 16 for operating a finishing float 20 which is provided at the rear of the carriage, so that 5 it will operate upon the concrete or plastic road building material after the latter has been acted upon by the rollers.

A conventional clutch 16^a on the worm gear shaft 16 controls the connection between the shaft and the chain and sprocket connection 18, and this clutch is operable from one end of the carriage by means of a rod 16^c which is journaled in suitable bearings and has a handle 16^b at the end thereof, (see Fig. 1^a). If desired means may also be provided for shifting the variable speed gear 19 from one end of the carriage. A 10 slideable and rotatable shaft 19^a may be provided for this purpose, said shaft having a suitable connection with the shifting lever of the variable speed gear and being provided at one end of the carriage with a handle 19^b.

25 *Roller mountings.*

The roller 7 operates in advance of the roller 8, and is preferably shorter than the roller 8, so that it can be lowered between the road rails 1 and adjusted to act initially 20 below the top of the road rails when such is desired. This advance roller 7 may be termed the "breaker" roller, while the roller 8 which is sufficiently long to extend over the tops of the road rails 1 may be termed the "finishing" roller. The breaker roller 7 may be lowered several inches more or less below the grade, so that it can act upon a 25 first course of concrete or plastic material in the event it is desired, to lay the road building material in a number of superposed layers or courses. The breaker roller 7 is also susceptible of being set at an elevation above the grade and the finishing roller 8 can be set directly upon the road rails 1 or at a 30 slight elevation above the same, as may be required by the character of work being done. The two rollers, 7 and 8 are suitably shaped to impart the desired crown to the road surface, being contracted at their middle portions and flared at their ends. The rollers extend longitudinally of the carriage in a spaced and parallel relation to each other so that they extend transversely across the road, and can be brought into engagement 35 with the freshly deposited and still plastic road building material after the latter has been deposited upon the subgrade by a paver or other suitable machine and roughly distributed over the subgrade between the road rails. The rollers 7 and 8 are provided with the respective shafts 7^a and 8^a and these shafts are journaled at their ends in the cross heads of a roller carrying frame. 40 These cross heads of the roller carrying frame are rigidly connected to a shaft 21,

which extends longitudinally of the carriage and is arranged between the two rollers, said shaft being journaled at opposite ends of the carriage in bearings 22, which are adjustably supported by hangers 23, so that they can be 45 raised and lowered for the purpose of adjusting the elevation of the rollers. One of the cross heads of the roller carrying frame is in the form of a hollow casing 24, (see Figs. 11, 12 and 13) within which the gear- 50 ing for selectively driving the rollers and longitudinally reciprocating the same is mounted. Both the gear casing 24 and the cross head at the opposite end of the roller carrying frame are connected by a strut 25 55 to a fixed portion of the carriage, said strut having universal joints at both ends thereof and serving to brace the roller carrying frame and take up the thrust thereon without interfering with the adjustments thereof. 60

Roller adjustments.

The hangers 23 for the bearings 22 of the roller supporting frame are connected at their upper ends to the middle portion of 65 crank shafts 26, one of these crank shafts being located at each end of the carriage, and the crank shafts being journaled within suitable bearings 27 which are applied to the tubular rods 3. One end of each of these 70 crank shafts is provided with a segmental worm gear 28 (see Figures 1 and 22), which meshes with a worm 29 on a roller adjusting shaft 30. The worm is loose upon the shaft and is held against longitudinal movement by the engagement of a bracket 31 with a collar 29^a at one end thereof. Clutch members 32 which are rigidly mounted upon the shaft 30 are adapted to be brought into 75 interlocking engagement with adjacent ends of the worms 29 for locking the worms with the shaft so that the two segmental worm gears 28 at opposite ends of the carriage can be simultaneously turned to rotate the crank shafts 26 and raise and lower the bearings 22 which support the roller carrying frame. The roller adjusting shaft 30 extends longitudinally of the carriage, being 80 journaled within suitable bearings and provided with a hand wheel 33 by means of 85 which it can be conveniently rotated in either direction.

Mechanism is also provided for rocking or tilting the roller carrying frame upon the shaft 21 as an axis for the purpose of adjusting the relative elevations of the two rollers 7 and 8. An arm 34 extends upwardly from the shaft 21 at each end thereof (see Figure 5), the lower ends of the arms being forked so that they straddle the 90 shaft and the forked ends being pivotally connected to collars 35, which are rigidly clamped upon the shaft. The upper ends of the arms 34 are connected by a double pivotal joint 36 to laterally extending rack mem- 95

bers 37 which engage pinions 38 on the roller adjusting shaft 30. These pinions are loose upon the shaft and are held against longitudinal movement by the bracket members 39 (see Figures 21 and 22). The pinions are also formed with notched flanges 38^a which are adapted to be engaged by detents or pawls 40 for the purpose of locking the pinions against rotation and holding the roller supporting frame in an adjusted position. The two pawls or detents 40 at opposite ends of the carriage are adapted to be simultaneously moved into and out of operative position and are rigid with a shaft 41 which extends longitudinally of the carriage, being journaled in suitable bearings and provided at one end thereof with a handle 42. By suitably manipulating this handle the two pawls are simultaneously moved and either disengaged from the notched flanges of the pinions or brought into an engagement therewith. The pinions 38 have clutch faces which are similar to the clutch faces of the worms 29, and which are adapted to be selectively engaged by the clutch members 32 of the roller adjusting shaft 30. When this shaft 30 is moved longitudinally in one direction the clutch members 32 are brought into engagement with the worms 29 so that a rotation of the shaft will raise or lower the roller supporting frame, while when the shaft is moved longitudinally in the opposite direction the clutch members 32 are brought into engagement with the pinions 38, so that a rotation of the shaft will result in tilting the roller carrying frame about the shaft 21 as an axis, with the result that one of the rollers will be lowered and the other roller elevated. This tilting action of the roller carrying frame for the purpose of adjusting the relative elevations of the two rollers is illustrated very nicely by the dotted lines on Figure 5 of the drawings.

The pivotal connections at the upper and lower ends of the upright arms 34 permit the rollers and roller carrying frame to reciprocate longitudinally in a manner to be hereinafter described, when this longitudinal reciprocation of the rollers is desired. After the roller supporting frame has been tilted into the desired angular position, the locking pawls 40 are brought into engagement with the notched flanges 38^a of the pinions 38, thereby holding the parts securely in their adjusted positions. The two adjustments of the roller carrying frame, namely, the raising and lowering thereof, and the tilting of the frame about its longitudinal axis, enable the two rollers to be adjusted and set in different relative positions. The breaker roller 7 can be set at any intermediate position between its extreme upper position which is usually several inches above the grade and its extreme lower position which is usually several inches below the

grade, while the finishing roller 8 can be set either upon the grade or at a variable elevation above the grade. A large number of different adjustments are possible, and the rollers can be set in that particular position which will enable the machine to operate in the most effective manner upon the concrete or other road building material.

Roller driving mechanism.

75

The before mentioned drive shaft 15 which is connected to the engine shaft 11 by the universal joint 14, has the outer end portion thereof fitted with a universal joint 43 and carried into the top of the gear casing 24 which is provided at one end of the roller carrying frame. (See Figures 11 to 14.) A pinion 44 is loosely mounted upon the portion of the shaft 15 which is within the casing 24, and a conventional form of clutch member 45 may be provided for locking the pinion with the shaft. This clutch member is shown as controlled by means of a handle 46, which projects through an opening in the front of the gear casing and which enables the clutch member to be moved into position for engaging or releasing the pinion. This controls the driving connection between the engine and the gearing for operating the rollers. The pinion 44 meshes with a gear wheel 47 which is keyed upon the shaft 48 with a worm 49 which meshes with a worm gear 50 on a shaft 51 extending longitudinally through the gear casing 24. The chain of gearing between the drive shaft 15 and the shaft 51 serves to reduce the speed so that the shaft 51 revolves at a much slower rate than the shaft 15.

One end of the shaft 51 is provided with a pair of reversely disposed bevel pinions 53 and 54 which are adapted to engage opposite sides of a bevel gear wheel 55 which is keyed upon the shaft 8 of the finishing roller 8, so that the said gear wheel can be rotated in opposite directions.

105

The opposite end of the shaft 51 is provided with a similar bevel pinion 57 which meshes with a bevel gear wheel 58 upon the shaft 7^a of the breaker roller 7. Conventional gear shifters 59 are provided for shifting the pinions 53, 54 and 57, and these gear shifters are selectively controlled by means of levers 60, which project through the front of the gear casing. The pinions are adapted to be locked in operative position by forked slides 61, which extend upwardly through the top of the gear casing (see Figure 14), and which have depressions 62 in the sides thereof for engagement with a spring pressed ball clutch 63 to lock the slides in either a raised or a lowered position. When the respective slides are lowered the corresponding bevel pinions are locked to rotate with the shaft 51 and the

115

120

125

130

roller or rollers are positively rotated. When all of the bevel pinions are permitted to rotate freely on the shaft 51 the rollers are not driven, and are permitted to idle 5 along upon the work as the carriage is propelled upon the road rails.

Roller reciprocating mechanism.

The rollers may or may not have a longitudinal reciprocated movement imparted thereto, depending upon the manner in which they are adjusted, and the character of work which is being performed. The shaft 51 is provided at an intermediate point in its length with an eccentric 64 (see Figure 6), and this eccentric operates within an eccentric band 65 at one end of a link 66. The opposite end of the link extends slidably through a sleeve 67 at the lower end of a hanger 68, which is suspended from the bracket 69 projecting from one of the arched cross pieces of the carriage. Coil springs 70 which surround the link 66 are interposed between opposite ends of the sleeve 67 and set collars 71 on the link so that a yielding connection is obtained between the link and the hanger. A rod 72 which is connected at one end to the hanger 68 has the other end thereof carried through an opening in one of the end cross pieces 2 of the carriage where it is provided with an opening into which a key 73 can be slipped. This key when it is dropped into operative position also engages corresponding openings in a tubular guide member 74 which is rigid with the cross piece 2 of the carriage. When the key 73 is fitted in position the hanger 68 is held against swinging, with the result that the rotation of the eccentric 64 operates through the link 66 to reciprocate the roller carrying frame longitudinally, the rollers of course being reciprocated with the frame. On the other hand, when the key 73 is removed the hanger 68 can swing or vibrate freely and the link 66 is itself reciprocated and does not meet with any resistance which would result in the reciprocation of the roller carrying frame. When it is desired to reciprocate the rollers longitudinally the key 73 is inserted in position, as indicated by Figure 6, while when a reciprocating movement of the rollers is not desirable the key is removed.

The finishing float mounting.

The finishing float 20 is arranged at the rear of the carriage so that it follows the rollers and acts upon the surface of the concrete after the rollers have gone over the concrete. The finishing float itself may be of any well known construction, and the float is supported by means of a series of arms 75 which are rigidly secured to a shaft 76, said shaft being arranged parallel to the tubular rods 3 of the carriage and being journaled in suitable bearings 77 at the ends of the arched cross pieces 2. The shaft is slidably within the bearings, so that it reciprocates back and forth with the finishing float, and one end of the shaft is provided with a handle portion 78 by means of which the shaft can be rotated to lift the finishing float above the surface of the concrete and swing it upwardly into an inoperative position, as indicated by dotted lines on Figure 15. The swinging ends of the arms 75 are detachably connected to the float, being shown as having the extremities thereof forked at 75^a to straddle fastening bolts 79. The arms of the forks are bent upwardly at 75^b to engage rectangular blocks 80, which are fitted upon the bolts. This provides a rigid connection between the float and the arms, although the float can be quickly detached from the arms when this is desired.

Finishing float reciprocating mechanism.

As has been previously indicated, a driving connection is provided between the finishing float and the worm gear shaft 16. This driving connection is illustrated more clearly by Figures 2^A and 15 of the drawings. The shaft 16 is provided with a crank wheel 81, which is connected by a pitman 82 to an arm 83 on a rock shaft 84 which extends transversely of the carriage. One end of this rock shaft terminates at a point adjacent the finishing float shaft 76, and is provided with an arm 85 which is connected to a reciprocating slide 86. This slide extends parallel to the finishing float shaft 76 and has the free end thereof loosely supported by a bracket 87, (see Figures 16, 17 and 18). The reciprocating slide 86 is provided with a downwardly facing notch 88, which is adapted to interlock with a pin 89 projecting from the finishing float shaft 76. The relation of the parts is such that when the finishing frame is swung downwardly into operative position the pin 89 will either engage the notch 88 or be brought automatically into engagement thereto as the slide 86 reciprocates, thereby completing the operative driving connection between the finishing float and the rock shaft, so that the finishing float will be reciprocated back and forth. When the finishing float is swung upwardly into inoperative position, as indicated by dotted lines on Figure 15, the pin 89 is automatically dis-engaged from the notch 88 and the driving connection broken between the finishing float and the rock shaft. If the pin 89 does not happen to enter the notch 88 when the finishing float is lowered into engagement with the surface of the concrete, it will initially lift the slide 86 and the slide will reciprocate over the top of the pin until the notch is brought into registry with the pin, at which time the slide will swing down into operative position and

the pin will enter the notch, thereby establishing an interlocking connection between the members. The worm gearing which is interposed between the rock shaft 84 and the engine greatly reduces the speed of rotation, so that the finishing float is rotated at the proper speed to give the most satisfactory results.

Carriage propelling means.

10 The variable speed gear device 19 serves to drive a pair of shafts 90 which project from opposite ends thereof and are transversely disposed with respect to the carriage. These 15 shafts are provided with suitable universal joints 91, and are inclined downwardly at the front and rear of the carriage, where they have the worms 92 applied to the end portions thereof (see Figures 7 to 10 of the 20 drawings.) These worms 92 engage worm gears 93 which are suitably mounted within the casing 94. Each of the worm gears 93 is provided with an elongated hub member 95 which receives the ends of the shafts 25 5. The extremities of the hub member project from opposite sides of the casing, and have internal gear members 96 keyed upon or otherwise rigidly applied thereto. Co-operating gear members 97 are keyed or 30 splined upon the respective shafts 5 and are adapted to be moved into or out of engagement with the respective internal gears 96. These gears 97 are carried by sleeves 98 which are fitted loosely upon the respective 35 shafts 5, being provided with pins 100 which are received within longitudinal slots in the shafts, so that the sleeves always rotate with the shafts, although they can be moved longitudinally thereon to bring the gears 97 40 into and out of mesh with the internal gear members 96 of the worm gear members. Coil springs 101 which surround the shafts 5 are interposed between the sleeves 98 and the collars 102 and normally tend to urge 45 the gears 97 into mesh with the internal gears 96. A collar 99 is swiveled upon each of the sleeves 98 and is held against rotation by an arm 99^b which is connected to some suitable portion of the main frame, as 50 indicated by Figure 10. Cam teeth 99^a are formed upon the collars 99, and arranged in cooperative relation with corresponding cam teeth 103^a on a ring 103 which is loosely mounted upon the sleeve 98. These rings 55 are provided with levers 104, and when these levers are moved to rotate the rings in one direction, the cam teeth 99^a and 103^a cooperate to move the collar 99 against the spring 101, and to break the clutch connection be- 60 tween the shafts and the worm gear, while when the levers are moved to rotate the rings in the opposite direction the shafts are locked with the worm gears. The two levers 104 controlling the drive wheels at each end 65 of the machine are connected for simultane-

ous action by a system of links and levers which is shown by Figure 4. A hand operating lever 105 is pivotally mounted between its ends upon the carriage, and the lower end thereof is connected by a link 106 to one of the levers 104, while an upper portion of the lever is connected by the two links 107 and the intermediate rock member 108 to the opposite lever 104. There is one of these hand operating levers 105 for the shafts 5 extending to each end of the carriage, and by properly manipulating these hand levers 105 all of the drive wheels 4 can be driven simultaneously, or the wheels at either end of the carriage can be driven independently of the wheels at the other end of the carriage. This latter arrangement may be advantageous when going around a curve. Of course when all of the clutches are disengaged there will be no power applied to the wheels 4 for propelling the carriage.

The universal point on the roller drive shaft.

The universal joint 14 which connects the engine shaft 11 with the roller drive shaft 15 has a peculiar construction and provides for the reciprocation of the shaft 15 relative to the engine shaft 11 when the mechanism is set to reciprocate the rollers and roller carrying frame longitudinally. The construction of the universal joint is shown in detail by Figures 23 and 24. The engine shaft 11 terminates in a socket 109 which loosely receives a knob or ball 110 at the end of the shaft 15. The socket is elongated so that the ball is free to slide back and forth therein when the shaft 15 reciprocates. Each of the shafts is provided with a pair of longitudinally projecting arms, and the arms of the respective shafts are connected by tension springs 112. The springs are strong enough to impart driving power from the shaft 11 to the shaft 15, although they are sufficiently flexible to permit of the endwise reciprocating movement of the shaft 15 without setting up undue stresses in any of the parts.

Operation of the machine.

113
While the finishing machine is especially adapted for use in the making of concrete roads and pavements, it will be understood that it can be used for the compacting and shaping of any analogous plastic material 120 which may be employed in road construction work. Road building machinery has been developed to such an extent that comparatively large areas of the subgrade can be covered with plastic concrete aggregate 125 from a paver or mixer which moves progressively along the subgrade as the road building operation proceeds, and the finishing machine of the present invention is mounted upon the usual side forms or road rails 130

and is power driven so that it can act upon the plastic concrete and be moved progressively along the road to keep up with the operations of the paver, the machine has 5 a sufficient amount of weight to hold the rollers to their work, and cause them to exert pressure upon the concrete aggregate. The rollers have a mechanical action upon the concrete and are adjusted so that they 10 tend to compress the same, and in being moved back and forth they have a kneading action upon the concrete which tends to bring surplus water and grout to the surface, so that a neat and durable finish can 15 be given by the finishing float which acts upon the surface of the concrete after the concrete has been subjected to the action of the rollers. The pressure exerted upon the concrete by the rollers results in obtaining 20 a dense concrete and serves to distribute the aggregate in such a manner as to give a superior wearing surface.

The two rollers 7 and 8 are adapted to be set at different elevations with respect to 25 each other. If it is desired to deposit the plastic concrete upon the subgrade in layers, the breaker roller 7 can be initially adjusted to act upon the first layer of concrete at a point below the grade, and subsequently 30 adjusted to act upon the succeeding layer or layers of concrete. The breaker roller 7 operates in advance of the finishing roller 8, and is preferably set at a slightly lower elevation than the finishing roller, since it accomplishes the heavier and rougher work. The rollers can either be connected with the engine so as to be positively rotated, or 35 they can be permitted to idle, and the finishing roller 8 can be positively rotated in either direction. Under some conditions the roller may be rotated in a direction opposed to the movement of the carriage, while under other conditions it may be rotated in a direction corresponding to the direction 40 of movement of the carriage. The rollers are also mounted in such a manner that they can be reciprocated longitudinally at the same time the carriage is moved, or permitted to act upon the concrete without this 45 reciprocating movement, at the option of the operator. When the key 73 is removed from position the rollers do not have the longitudinally reciprocating movement, while when the key is replaced the rollers 50 are reciprocated longitudinally and thereby caused to have an additional mechanical action upon the plastic concrete. The adjustment of the rollers is controlled by a single hand wheel 33 and by properly manipulating this hand wheel the rollers can 55 be raised or lowered and set at different relative elevations.

The finishing float 20 follows the rollers and acts upon the surface of the concrete in 60 a well known manner to leave a smooth sur-

face at the top of the road. The finishing float can be readily swung into and out of operative position. All of the mechanism of the machine is under the complete control of the operator, and the many possible adjustments of the rollers and the driving means for the rollers enable the machine to be set for the most efficient action under many different conditions of use. The rollers may be driven at different speeds, 70 for instance, the gearing may be such as to drive the finishing roller at a speed of thirty-five (35) revolutions per minute and the breaker roller at a speed of twenty-five (25) revolutions per minute, and this differential 75 rotation of the rollers may be helpful in getting the best results. Obviously there are many conditions under which the finishing roller can rotate to advantage at a higher rate of speed than the breaker roller which 80 has heavier work to perform. The finishing machine is power driven and operates across the entire width of the road so that the concrete can be compacted and molded into shape as rapidly as it is deposited upon the 85 subgrade by the paver. A machine of this kind greatly increases the rapidity with which a road can be built, and at the same time tends to decrease the expenses and cost by decreasing the amount of labor necessary 90 and avoiding delays. At the same time a road is built which is composed of stronger concrete and which is substantially uniform in density throughout its entire length, since all of the concrete receives substantially the 95 same treatment.

Having thus described my invention what I claim as new and desire to secure by Letters Patent is,

1. A machine for finishing concrete while 105 in a plastic state, including a carriage with its own means of traveling, a plurality of rollers supported by the carriage for operating on the plastic concrete, and means for raising or lowering together and for raising 110 one roller and at the same time lowering another.

2. A machine for finishing concrete while 115 in a plastic state, including a carriage with its own means of traveling, a plurality of rollers supported by the carriage for operating on the plastic concrete, and means for lifting and lowering the rollers together and means for lifting one roller and simultaneously lowering another roller.

3. A machine for finishing concrete while 120 in a plastic state, including a carriage with its own means of traveling, a plurality of rollers supported by the carriage for operating on the plastic concrete, and means for moving the rollers vertically and rocking them in opposite directions.

4. A finishing machine for pavement 125 while in plastic state including a carriage, a roller mounted thereon, means for selec- 130

- tively driving the roller in either direction, and means to move the machine backward or forward while driving the roller in either of opposite directions.
5. A finishing machine for pavement while in plastic state including a carriage, a roller mounted thereon, and means for selectively driving the roller in either direction or permitting the roller to idle with respect to the driving mechanism.
10. A finishing machine for pavement while in plastic state including a carriage, a roller mounted thereon, means for selectively driving the roller or permitting it to idle with respect to the driving mechanism and means for reciprocating the roller longitudinally.
15. A pavement finishing machine including a carriage, a plurality of rollers thereon, and means for driving the rollers at different speeds and causing the rollers to revolve either in the same direction or in opposite directions.
20. A pavement finishing machine including a carriage, a plurality of rollers mounted thereon, means for driving the rollers at different speeds, and means for reciprocating the rollers longitudinally.
25. A pavement finishing machine including a carriage, a pair of rollers mounted thereon, means for selectively driving the rollers or permitting them to idle, means for reversing the direction of rotation of one of the rollers, and means for reciprocating the rollers longitudinally.
30. A pavement finishing machine including a carriage adapted to travel upon the usual side forms, a finishing roller carried by the frame and extending over the side forms, a breaker roller carried by the frame and being shorter than the finishing roller so that it can be lowered between the side forms to act upon the road making material at a point below the final grade, and means for adjusting the position of the breaker roller.
35. A pavement finishing machine including a carriage, a roller carrying frame mounted thereon, a roller journaled upon the frame, and means for reciprocating the frame with the roller longitudinally respecting the latter.
40. A finishing machine including a carriage having its own traveling means, a roller supporting frame mounted thereon, a roller journaled upon the frame, for acting on plastic concrete pavement, means for reciprocating the frame longitudinally, and means for adjusting the frame to adjust the position of the roller.
45. A pavement finishing machine including a traveling carriage supported independent of the work to be finished, a roller supporting frame mounted thereon to have a swinging and reciprocating movement, a roller journaled upon the frame, means for swinging the frame to adjust the position of the roller and means for reciprocating the frame.
50. A pavement finishing machine including a traveling carriage supported independent of the work to be finished, a roller supporting frame mounted thereon to have both a swinging and a reciprocating movement, a roller journaled upon the frame, means for tilting the frame to adjust the position of the roller, means for driving the roller, and means for reciprocating the frame.
55. A pavement finishing machine including a carriage, a roller supporting frame mounted thereon to have both a swinging and a reciprocating movement, a roller journaled upon the frame, means for selectively driving the roller in either direction, means for tilting the frame to adjust the position of the roller, and means for reciprocating the frame.
60. A pavement finishing machine including a carriage, a roller, a roller supporting frame mounted upon the carriage to reciprocate in the direction of the axis of the roller, means for raising and lowering the frame to adjust the elevation of the roller, a shaft journaled upon the frame, means actuated by the shaft for reciprocating the frame, an engine upon the carriage, and a driving connection between the engine and the shaft including yieldably connected members of which one can reciprocate with respect to the other.
65. A pavement finishing machine including a carriage, a roller, a roller supporting frame mounted upon the carriage to have a reciprocating motion, means for raising and lowering the frame to adjust the elevation of the roller, a shaft journaled upon the frame, means actuated by the shaft for reciprocating the frame, an engine mounted upon the carriage, and a driving connection between the engine and the shaft including shaft sections having a loose telescoping connection at their adjacent ends, and provided with lateral arms yieldably connected to each other whereby one shaft section can reciprocate relative to the other shaft section.
70. A pavement finishing machine including a carriage, a roller, a roller supporting frame, means for raising and lowering the frame, means for tilting the frame, and a single operating member controlling both the raising and lowering means and the tilting means.
75. A pavement finishing machine including a carriage, a roller, a roller supporting frame, means for raising and lowering the frame, means for tilting the frame, an operating shaft, and means actuated by the longitudinal movement of the shaft for locking it with either the raising or lowering means or the tilting means.

- ing a carriage, a roller, a roller supporting frame, gearing for adjusting the frame in one direction, independent gearing for another adjustment of the frame in a different direction, an operating shaft, and clutch means for selectively connecting the shaft with either set of gearing. 70
21. A pavement finishing machine including a carriage, a roller, a roller supporting frame, gearing for an adjustment of the frame up or down, gearing for another adjustment of the frame to control the action of the roller on plastic substances, an operating shaft, and clutch means controlled by a longitudinal movement of the shaft to lock the shaft with either set of gearing, the second adjustment of the frame being in direction different from the first mentioned adjustment. 75
22. A pavement finishing machine including a carriage, a plurality of rollers, gearing for raising and lowering the rollers, independent gearing for adjusting the relative elevations of the rollers, and a single operating member adapted to be selectively brought into engagement with either set of gearing. 80
23. A pavement finishing machine including a carriage, a roller, a roller supporting frame, crank shafts for the roller supporting frame, and means for simultaneously turning the crank shafts to raise or lower the frame. 85
24. A pavement finishing machine including a carriage, a roller, a roller supporting frame mounted to have a tilting movement, an arm projecting from the frame, and gearing associated with the arm for swinging the same to tilt the frame. 90
25. A pavement finishing machine including a carriage, a roller, a roller supporting frame mounted to have a tilting movement, crank shafts from which the frame is suspended, means for simultaneously rotating the crank shafts to raise and lower the frame, an arm projecting from the frame, and gearing associated with the arm for tilting the frame. 95
26. A pavement finishing machine including a carriage, a roller, a roller supporting frame mounted to have a tilting movement and also to reciprocate, crank shafts, hangers loosely suspending the frame from the crank shafts, means for turning the crank shafts to raise and lower the frame, arms carried by the frame and pivotally connected thereto to permit of the reciprocation of the frame, racks loosely connected to the arms and gearing associated with the racks for tilting the frame. 100
27. A pavement finishing machine including a carriage, a pair of rollers, a roller supporting frame including a rod arranged parallel to the rollers, bearings on the rod, hangers supporting the bearings, means associated with the hangers for cooperation therewith to raise and lower the frame, and means for rocking the rod in the bearings to tilt the frame into different angular positions. 105
28. A pavement finishing machine including a carriage, a pair of rollers, a roller supporting frame including a rod extending parallel to the rollers, bearings applied to the rod, hangers engaging the bearings, means associated with the hangers for raising and lowering the frame, an arm projecting from the rod, a laterally projecting rack bar pivotally connected to the arm, and gearing cooperating with the rack bar to swing the arm and tilt the frame. 110
29. A pavement finishing machine including a carriage, a pair of rollers, a roller supporting frame including a rod extending parallel to the rollers and mounted to reciprocate in the direction of the axis of the rod, bearings applied to the rod, hangers pivotally connected to the bearings, means associated with the hangers for raising and lowering the frame, an arm pivotally connected to the rod to swing about an axis at right angles thereto, a rack bar loosely connected to the arm, gearing associated with the rack bar for swinging the arm to rotate the rod and tilt the frame and means for reciprocating the frame. 115
30. A pavement finishing machine including a carriage, a pair of rollers, a roller supporting frame including a rod extending parallel to the rollers, said frame being adapted to reciprocate in the direction of the rod, bearings applied to the rod, hangers pivotally connected to the bearings, gearing associated with the hangers for raising and lowering the frame and supporting it at different elevations, an arm projecting from the rod and connected thereto to swing about an axis at right angles to the axis of the rod, gearing associated with the arm for rocking the rod to tilt the frame, and a single operating member through which either set of gearing can be selectively operated. 120
31. A pavement finishing machine including a carriage, a roller, a roller supporting frame including a rod, bearings on the rod, hangers pivotally connected to the bearings, means associated with the hangers to raise and lower the frame and support it at different elevations, an arm projecting from the rod and pivotally connected thereto to swing about an axis at right angles to the rod, gearing associated with the arm for rocking the rod to tilt the frame, a shaft journaled upon the frame, means actuated by the shaft for reciprocating the frame in the direction of the rod, an engine upon the carriage, and a driving connection between the engine and the shaft including shaft 125

sections connected by a flexible joint enabling one shaft section to reciprocate relative to the other shaft section.

32. A pavement finishing machine including a carriage, a roller, a roller supporting frame formed with a rod and adapted to reciprocate in the direction of the rod, bearings on the rod, hangers pivotally connected to the bearings, means associated with the hangers for raising and lowering the frame and supporting it at different elevations, an arm projecting from the rod and pivotally connected thereto to swing about an axis at right angles to the rod, gearing associated with the arm to rock the rod and swing the frame, a shaft journaled upon the frame, means actuated by the shaft for driving the roller, means actuated by the shaft for reciprocating the frame, an engine upon the carriage, and a yieldable driving connection between the engine and the said shaft.

33. A pavement finishing machine including a carriage, a pair of rollers, a roller supporting frame upon the carriage, means for adjusting the position of the frame, a shaft journaled upon the frame and extending across the ends of the rollers, gearing between the shaft and one of the rollers for driving the roller in one direction, and selectively controlled gearing between the shaft and the other roller for driving the said roller in either direction.

34. A pavement finishing machine including a carriage, a breaker roller, a finishing roller, a driven shaft extending across the ends of the roller, gearing between the shaft and the breaker roller for driving the roller in one direction, and selectively controlled gearing between the shaft and the finishing roller for driving the finishing roller in either direction.

35. A pavement finishing machine including a carriage having traction wheels, movably mounted pavement finishing means thereon, an engine mounted upon the carriage and having a driving connection with the pavement finishing means, and a selectively controlled driving connection between the engine and the traction wheels at opposite ends of the carriage whereby the wheels at the opposite ends of the carriage can be differentially driven when making a turn.

36. A pavement finishing machine including a carriage having traction wheels at opposite ends thereof, an engine upon the carriage, shafts driven from the engine, short shafts driven from the said shafts and arranged between corresponding traction wheels at opposite ends of the carriage and selectively controlled means for operatively connecting the traction wheels with the said shafts.

37. A pavement finishing machine including a carriage having traction wheels at opposite ends thereof, an engine mounted

upon the carriage, transversely extending shafts driven from the engine, longitudinally extending shafts geared to the transverse shafts and arranged between corresponding traction wheels at opposite ends of the carriage, clutch means for operatively connecting the traction wheels to the corresponding shafts, and independent means for collectively controlling the clutch means at each end of the carriage.

38. A pavement finishing machine including a carriage having corresponding traction wheels at opposite ends thereof, an engine mounted upon the carriage, transverse shafts driven from the engine, longitudinally extending shafts geared to the transverse shafts and arranged between corresponding traction wheels at opposite ends of the carriage, clutch means for connecting the traction wheels to the respective shafts, yielding means normally tending to close the clutches, and means for collectively opening the clutches for the traction wheels at each end of the clutch.

39. A pavement finishing machine including a carriage having traction wheels, an axle for each traction wheel, short shafts interposed between the axles for corresponding traction wheels at opposite ends of the clutch, clutch means for selectively connecting the axles to the respective shafts, an engine upon the carriage, and means for driving the shafts from the engine.

40. A pavement finishing machine including a carriage having corresponding traction wheels at opposite ends thereof, an axle for each traction wheel, shafts interposed between the ends of axles for corresponding traction wheels on opposite ends of the clutch, clutch means for connecting the axles to the corresponding shafts, means for collectively controlling the clutch members for all of the traction wheels at either end of the carriage, an engine, and means for driving the shafts from the engine.

41. A pavement finishing machine including a carriage having corresponding traction wheels at opposite ends thereof, an axle for each traction wheel, a shaft interposed between the axles of corresponding traction wheels at opposite ends of the clutch, an engine, transversely extending shafts driven from the engine and connected by speed reducing gearing to the shafts, clutches for connecting the axles to corresponding shafts, and means for collectively operating the clutch members for all of the traction wheels at either end of the carriage.

42. A pavement finishing machine including a carriage, a float, a shaft carrying the float and mounted to have both a reciprocating and a rotary movement, the rotary movement enabling the float to be swung upwardly into inoperative position, an engine upon the carriage and a driving con-

- nection between the engine and the float comprising a notched reciprocating link arranged parallel to the shaft and a pin projecting radially from the shaft and moved 5 automatically into and out of engagement with the notched link as the float is swung into and out of operative position.
43. A pavement finishing machine including a carriage, a finishing float, a shaft 10 mounted upon the carriage to have both a reciprocating and a rotary movement, said shaft carrying the finishing float and the rotary movement of the shaft enabling the finishing float to be swung into inoperative 15 position, an engine upon the carriage, a shaft arranged transversely with respect to the first mentioned shaft and driven from the engine, an arm upon the shaft, a reciprocating notched link connected to the arm, 20 and a radial pin projecting from the float carrying shaft and arranged to be moved into and out of engagement with the notched link as the float is swung into and out of operative position.
- 25 44. A pavement finishing machine including a carriage having traction wheels, a roller, a finishing float, an engine mounted upon the carriage, a driving connection between the engine shaft and the roller, speed 30 reducing gearing driven from the engine shaft and having a driving connection with the finishing float, variable speed gearing driven from the said speed reducing gearing, and an operative connection between the 35 variable speed gearing and the traction wheels of the carriage.
45. A pavement finishing machine including a carriage, a finishing roller carried thereby, means for raising and lowering the 40 finishing roller, and selectively controlled means for positively driving the roller in a predetermined direction relative to the movement of the carriage, or permitting the roller to idle during movement of the carriage, and 45 means supporting the carriage independently of the road surface adapted to be operated upon by the finishing roller.
46. A finishing machine for concrete pavement work, to finish the concrete materials 50 while in plastic state, comprising a carriage adapted to operate over the surface to be finished and supported independently of said surface, a roller mounted on said carriage, means to raise and lower the roller, and 55 means to turn the roller in the direction of movement of the carriage or in an opposite direction.
- 60 47. A finishing machine for concrete pavement work, to finish the concrete materials while in plastic state, comprising a carriage adapted to operate over the surface to be finished and supported independently of said surface, a roller mounted on said carriage, means to raise and lower the roller, means 65 to turn the roller in the direction of move- 70 ment of the carriage or in an opposite direction, and means for permitting the roller to idle during movement of the carriage and under the influence of contact with the road materials being finished.
48. In a machine for finishing concrete pavement while in plastic state, the combination of a portable carriage adapted to travel over the surface to be finished and supported independently of said surface, a 75 plurality of finishing rollers on said carriage, and means for driving one roller at relatively high speed and another roller at relatively low speed.
49. In a machine for finishing concrete 80 pavement while in plastic state, the combination of a portable carriage adapted to travel over the surface to be finished and supported independently of said surface, a 85 roller mounted on said carriage for co-operation with the surface to be finished, supporting means for the roller mounted on the carriage, and common means for raising and lowering said supporting means, and for rocking it to impart desired adjustments 90 to the roller.
50. A finishing machine for pavement while in plastic state, including a carriage, a plurality of rollers thereon mounted on 95 separate axes, and means for driving the rollers at different speeds, and means to move the machine backward or forward while driving the roller in either of opposite directions.
51. A finishing machine for pavement 100 while in plastic state, including a carriage, a plurality of rollers thereon mounted on separate axes, and means for selectively driving the rollers either in the same direction or in reverse directions, and means to move the machine backward or forward while driving the roller in either of opposite directions.
52. A machine for finishing concrete while 110 in a plastic state, including a carriage with its own means of traveling, a roller supported by the carriage for operating on the plastic concrete, a roller supporting frame, means for reciprocating the frame, and means to cause said reciprocating means to discontinue its actuation of the frame.
53. A machine for finishing concrete while 115 in a plastic state, including a carriage with its own means of traveling, a roller supported by the carriage for operating on the plastic concrete, linkage mechanism for reciprocating the roller, and means to cause the said linkage mechanism to discontinue its actuation of the roller.
54. A machine for finishing concrete while 120 in a plastic state, including a carriage with its own means of traveling, a roller supported by the carriage for operating on the plastic concrete, linkage mechanism for reciprocating the roller, a movable support for 125
- 65 70 75 80 85 90 95 100 105 110 115 120 125 130

- the linkage mechanism, and releasable means for holding the support in operative position for causing reciprocation of the roller, the linkage mechanism being rendered inoperative when the said means is released.
5. A machine for finishing concrete while in a plastic state, including a carriage with its own means of traveling, a roller supported by the carriage for operating on the plastic concrete, a roller supporting frame, an eccentrically operated link connected to the frame for reciprocating the same, a movable bearing for the link, and releasable means for locking the bearing for causing reciprocation of the roller, the link mechanism being rendered inoperative when said means is released.
56. A machine for finishing concrete while in a plastic state, including a carriage with its own means of traveling, a roller supported by the carriage for operating on the plastic concrete, a roller supporting frame, a shaft on the frame, a link having an eccentric connection with the shaft and serving to normally reciprocate the frame, a support for the link, and means for rendering the support inoperative when it is not desired to reciprocate the frame.
57. A machine for finishing concrete while in a plastic state, including a carriage with its own means of traveling, a roller supporting frame mounted to be reciprocated, a shaft upon the frame, a link having an eccentric connection with the shaft, a swinging support for the link, a rod connected to the swinging support, and means for locking the rod and support so that the link will reciprocate the frame, the link being rendered inoperative when the rod is released.
58. A machine for finishing concrete while in a plastic state, including a carriage with its own means of traveling, a roller supported by the carriage for operating on the plastic concrete, a roller supporting frame mounted to have a reciprocating movement, an engine upon the carriage, a shaft journaled upon the frame, a yieldable driving connection between the engine and the shaft, means upon the shaft for driving the roller, a link having an eccentric connection with the shaft and also connected with the carriage to reciprocate the frame, and means for rendering inoperative the link device.

In testimony whereof I affix my signature.

GEORGE E. WEBB.
